Primary Examiner — Eric L Goodman*Assistant Examiner* — Michael Hoffman(74) Attorney, Agent, or Firm — Morgan, Lewis & Bockius LLP(57) CLAIM

The ornamental design for an aromatherapy facemask clip, as shown and described.

DESCRIPTION

FIG. 1 is a perspective view of an aromatherapy facemask clip showing our new design;

FIG. 2 is a right-side elevational view thereof;

FIG. 3 is a left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines illustrate structure or features that form no part of the claimed design.

1 Claim, 4 Drawing Sheets(56)
